UNITED STATES PATENT OFFICE.

EDWARD LOUIS SEAMAN, OF MASSILLON, OHIO.

SOLDERING-TOOL.

No. 924,110.

Specification of Letters Patent.

Patented June 8, 1909.

Application filed July 1, 1908. Serial No. 441,514.

To all whom it may concern:

Be it known that I, EDWARD LOUIS SEAMAN, a citizen of the United States, and a resident of the city of Massillon, in the 5 county of Stark and State of Ohio, have invented a new and Improved Soldering-Tool, of which the following is a full, clear, and exact description of the invention, such as will enable others skilled in the art to 10 which it appertains to make and use the same.

My invention relates to devices whereby the soldering of various articles of manufacture in large numbers may be conveniently, rapidly and cheaply effected, and it is the 15 object of the improvement to secure a steady and continuous flame within the combustion chamber of the soldering tool furnishing a maximum of heat with a minimum of gas.

Another object of my invention is to prevent 20 the back action of the flame.

A further object is the construction whereby the tool may be rotated axially upon the supply pipe, but not moved longitudinally thereof.

25 A still further object is the insulation of the soldering bolt, and the combustion chamber.

In order that my invention may be more fully understood, I have appended hereunto 30 a sheet of drawing showing my invention practically carried out, in which—

Figure 1, is a central longitudinal section of the combustion chamber. Fig. 2, is a central longitudinal section of the handle. Fig. 3, is a side elevation. Fig. 4, is a cross section through the dotted line *w. w.* Fig. 5, is a cross section through the dotted line *y. y.* Fig. 6, is a cross section through the dotted line *z. z.* Fig. 7, is a cross section through the dotted line *x. x.*, and Fig. 8 is a central longitudinal section through an alternative form of soldering bolt.

Similar characters of reference indicate corresponding 45 parts in the several figures.

The letter *a.* in the drawings represents the outer tubular casing of the combustion-chamber having air inlets at *l.* and an internal lining *b.* of heat insulating material 50 such as asbestos or the like, the rear end being flanged inwardly and permanently attached to the connecting yoke *f.* as shown at 10. Removably secured to the interior of the combustion chamber *a.* between the flange 55 10. and the sheet metal ring *g.* is a gauze-screen *h.* covering the rear of the combus-

tion-chamber which is more plainly shown in Fig. 7. Secured by means of the screw *n.* at the forward end of the casing *a.* is an annular sleeve of heat insulating material *o.* 60 more fully shown in Fig. 6. said sleeve having a central longitudinal perforation through which passes the soldering bolt *d.* extending within the combustion chamber and secured by means of the screw *m.* passing 65 through but not in contact with the casing *a.* Attached to the bolt *d.* and adjacent to the air inlets *l.* is an annular flanged sleeve serving to retain the flame within the combustion chamber. To the forward 70 end of the bolt *d.* is detachably screwed the soldering tip *c.*, or the tip *c.*, and the bolt *d.* may be forged in one piece as shown at *d.* in Fig. 8. tubular stem *e.* having diametrically opposite perforations at *k.* is permanently attached at the forward end to the 75 yoke *f.* at the rear end is exteriorly screwed the cap *t.* having a central longitudinal perforation through which passes the inner tubular member *j.* having a thin annular 80 flange *v.* thereon adapted to engage loosely between the rear end of the stem *e.* and the interior of the cap *t.* whereby the tool may be rotated axially upon the supply pipe but not moved longitudinally thereof. At the 85 forward end of the tube *j.* is exteriorly screwed, and fitting freely within the stem *e.*, a cap *i.* having a minute orifice *e:* adjacent to the openings at *k.* the combination of parts serving as a Bunsen burner. 90

s. represents a wooden handle having a central longitudinal perforation through which passes the stem *e.* secured thereon by means of the set screw *r.* screwed into the ferrule *p.* which is secured to the handle *s.* 95 by means of the wood screw *q.* A section of the handle being shown in Fig. 5.

In operation it is only necessary to connect the tube *j.* by means of the flexible hose *u.* to a gas fixture and turn on the gas which 100 enters the tube *j.* and escapes at the orifice *e:* passing down the stem *e.* where it mixes with the necessary amount of air. Passing across the gap *f:* impinging upon and passing through the gauze-screen *h.* into the 105 combustion chamber. The tool is then held downward and lighted at the annular opening between the lining *b.* and the flange at the air inlets at *l.* where it burns. With a sudden forward motion of the tool, the flame 110 retreats to within the combustion chamber.

The above described soldering tool will be

round light, simple and handy. A high degree of heat can be given to the bolt in a very short time, and the bolt will not cool while in use; and the combustion is regulated so that a very efficient device for the purpose is produced.

I have shown certain construction for purpose of illustration, but it is of course evident that the construction may be varied 10 without departing from the spirit of my invention, I therefore do not wish to be limited to the construction shown.

Having thus described my invention, I claim and desire to secure by Letters Patent—

1. In a gas heated soldering tool, the combination of means whereby the tool may be rotated axially independent of the supply pipe, comprising a tubular handle stem having a cap provided with a longitudinal perforation secured to its rear end, a tubular supply pipe passing through said cap provided with a flanged web portion adapted to engage loosely between the tubular handle 20 stem and the interior of said cap, a burner cap having a minute gas outlet orifice secured to the forward end of said supply pipe adapted to fit loosely within said handle stem, with a combustion chamber, and 25 a soldering bolt, substantially as set forth.

2. A gas heated soldering tool comprising a handle, a handle stem, a supply pipe, a combustion chamber having an insulating lining, an annular web or flange at its front 30 end, air passages adjacent to the flange, an inward extending flange at its rear forming a contracted opening to the chamber, a gauze screen in said opening, and yoke arms con-

nected said combustion chamber and handle stem, substantially as set forth. 40

3. In a gas heated soldering tool the combination of a handle having a longitudinal perforation, a handle stem through said perforation, a cap secured to the rear end of said handle stem, a supply pipe passing 45 through said cap, a flanged web on said supply pipe engaged loosely between said handle stem and cap, a burner cap having a minute gas outlet orifice and secured to the forward end of said supply pipe, the burner cap fitting loosely within said stem, air inlets in the handle stem adjacent to said burner cap, with a combustion chamber, yoke arms connecting said handle stem to said combustion chamber forming an air gap 55 between said combustion chamber and handle stem, the walls of said combustion chamber being inwardly flanged at the rear forming a contracted opening, a screen gauze over said opening, a heat insulating lining 60 within said combustion chamber, air inlets in the casing of the combustion chamber, a sleeve secured to the forward end of said combustion chamber, a soldering bolt passing through and secured to said sleeve, and a flanged web secured within said combustion chamber adjacent to said air inlets, substantially as set forth.

In testimony whereof, I have signed my name to this specification in the presence of 70 two subscribing witnesses.

EDWARD LOUIS SEAMAN.
